VIBRATOR

Application filed December 29, 1926. Serial No. 157,653.

This invention relates to vibrators and more particularly to vibrators adapted to be mounted upon the hand to impart to the hand a vibratory movement for massaging purposes.

One of the objects of the invention is to provide a device of the above nature which is practical and highly efficient. Another object is to provide a device of the above nature which is not bulky nor clumsy to handle and which is therefore convenient to use. Another object is to provide a device of the above nature which permits maximum freedom of movement of the hand. Another object is to provide a device of the above nature which is of light weight. Another object is to provide a device of the above nature which is simple and inexpensive. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which are shown one or more of the various possible embodiments of this invention,

Figure 1 is a side elevation of a vibrator mounted upon a hand, a portion of the motor casing being broken away in order to show the inner structure;

Figure 2 is a section taken along the line 2-2 of Figure 1;

Figure 3 is a sectional view showing an end portion of the motor casing and parts mounted therein, in a modified form of construction;

Figure 4 is a section taken along the line 4-4 of Figure 3;

Figure 5 is a perspective view showing a modified form of mounting upon the hand;

Figure 6 is a side elevation showing a different form of mounting for the motor;

Figure 7 is a view taken from the left hand side of Figure 6, parts thereof being broken away;

Figure 8 is a view from the opposite side of Figure 6, and

Figure 9 is a sectional view similar to Figure 3 but showing a modified construction.

Similar reference characters refer to similar parts throughout the several views of the drawing.

Referring now to the drawing in detail there is shown in Figure 1 a supporting frame 6 which is mounted through pads 13 and 13c upon the back of the hand. The pads 13 and 13c are of a yielding material such as sponge rubber or felt or the like, and they are preferably secured to the frame 6, for example by split rivets 12. These rivets do not extend all the way through the pads, thereby to avoid coming into contact with the flesh of the hand.

Directly upon the frame 6 is mounted an electric motor, the casing of which is designated by the reference numeral 1. The frame 6 is preferably made in the shape of a saddle, as shown in Figure 2, to receive the motor casing and, as shown in Figures 1 and 2, the motor casing is rigidly secured to the frame by screws 7. Preferably there is interposed between the motor casing and the frame 6 a suitable heat insulating material 14, for example asbestos, which prevents transmission of heat from the motor casing to the frame. The motor is very small and light and is not cumbersome to carry upon the back of the hand. It is driven at high speed and, through the pads 13 and 13c, it imparts to the hand a rapid vibratory movement as will be explained hereinafter.

Any suitable means may be employed to fasten the frame 6 in position upon the back of the hand. In Figure 1 there are shown a pair of straps 25a and 25b which pass around the hand. These straps 25a and 25b are preferably of fabric and they may be secured to the frame 6 in any desired manner, for example passing through slots 13a as indicated in Figure 1. If desired, instead of the straps 25a and 25b, coiled springs may take the place of the straps, as is indicated at 25c in Figure 1.

Another method of fastening the device upon the back of the hand is illustrated in

Figure 5. The pads 13 and 13c are secured in any suitable manner to a glove 23 having the fingers thereof cut off. This glove is preferably made of an elastic material so that it will stretch to fit various sized hands and it may be fastened upon the hand by any suitable means such as a strap 23a. Whether the straps 25a and 25b, or springs 25c or a glove 23 be employed, the forward pad 13 preferably rests on the back of the fingers near the middle knuckles, and preferably upon only the two middle fingers. When the straps 25a and 25b or the springs 25c are employed, the one associated with the front pad 13 preferably encircles only the two middle fingers, as is shown in Figure 1. When the glove 23 is employed, as shown in Figure 5, the pad 13 is preferably of a width to rest above the two middle fingers substantially in the position mentioned.

In employing a mechanism of this type for massaging, the massaging is ordinarily done with the fingers, and the mounting just described gives a vigorous vibratory movement to the fingers. When the glove support 23 is employed the omission of the glove fingers, as mentioned above and as shown in Figure 5, permits the usual massaging action by the fingers of the hand.

Referring again to Figures 1 and 2, there is shown the armature shaft 9 of the electric motor mounted in bearings 8 and 8a at the two ends of the casing 1. Upon this armature shaft is shown the rotor 4 having windings 16, the stator comprising windings 17 supported on the inner wall of the casing 1. The interior of the casing is provided with suitable cooling means preferably taking the form of a fan 3 rotating with the armature shaft, the casing having end openings 15 to permit passage of a current of air through the casing. This motor, it will be understood, is of the induction type so that no commutator or slip rings are employed. The wires for leading current to and from the stator 17 are indicated entering the top of the casing at 17a and 17b.

As is shown in Figure 1, and more clearly in Figure 2, the rotor 4 is made so that it will run out-of-balance. As shown in these figures, this is accomplished by cutting away portions of the rotor at 5 on one side of the axis thereof and between the windings 16. The result is that one side of the rotor is heavier than the other, and as it is rapidly rotated this out-of-balance construction gives a rapid vibratory movement which is transmitted through the armature shaft 9, the casing 1 and the frame 6 to the hand. It will be seen that this construction is extremely simple and inexpensive and that the out-of-balance feature for causing the vibrations is accomplished without adding any weight to the motor.

In Figures 3 and 4 there is shown a modi-

fied form of this construction. The motor casing 1 is extended outwardly at the end in the form of a cap 1a which encloses the end of the shaft 9. Within this cap portion 1a there is mounted upon the shaft 9 to rotate therewith a radially projecting arm or weight 10. This part 10 is secured to the shaft preferably by a key 21 held in place by a set screw 19 provided with a lock nut 20. The member 10 gives substantially the same effect as do the cut away portions 5 of the rotor shown in Figures 1 and 2. The armature shaft 9 runs out-of-balance and the centrifugal force of the rapidly rotating parts gives to the motor casing and thence to the hand a rapid vibratory movement. The out-of-balance member 10 is preferably mounted upon the end of the armature shaft which is positioned over the fingers so that this end of the device receives the direct thrust of the vibrations, the other end thereof which rests upon the back of the hand serving as a sort of anchorage about which the finger end vibrates. It will be seen that the construction shown in Figures 3 and 4 is simple and easily made, requiring simply the fastening of the out-of-balance member 10 to the armature shaft.

Referring now to Figure 6, in the construction shown therein, the frame 6 is split into two parts, a part 6a to which the front pad 13 is secured and the part 6b to which the rear pad 13c is secured. These two frame parts are connected by a member 30d which is preferably a flat strip of spring metal. The part 30d holds the two frame portions 6a and 6b apart but permits relative movement thereof in an up and down direction while preventing relative lateral movement. By means of this construction the front frame portion 6a and its pad 13 which rests upon the fingers may be given an up and down vibratory movement, while the rear frame portion 6b with its pad 13c remains substantially stationary.

Extending upwardly from the frame portion 6b is a bracket 27 in which the rear end of the motor casing 1 is swiveled about a horizontal axis as by trunnions 27a. Adjacent the front end of the motor casing 1 are a pair of ears 29 through which pass vertical rods 28. These rods are swiveled at their lower ends about pins 30a in lugs 30 projecting upwardly from the frame portion 6a. About the rod 28 beneath the ear 29 is a spiral compression spring 28d which is adjustable by means of a nut 28b threaded upon the rod. About the rod 28 above the ear 29 is a second spring 28a which is adjustable by means of a nut 28c.

With the construction shown in Figures 6, 7 and 8, the vibratory movement effected by the rotating armature shaft of the motor is transmitted to the frame portion 6a and thence to the fingers through the springs 28a

and 28d. As the front end of the motor rapidly vibrates, the motor oscillates about the trunnions 27a and the frame portion 6b, which is supported upon the back of the hand, remains substantially stationary. The full effect of the vibrations is felt in the fingers where it is most desired. The spring connecting member 30d permits this vibratory movement of the front end of the motor, but holds the motor against side sway. The vibration impulses are transmitted to the hand through the resilient springs 28a and 28d which may be made to cushion the shocks to any desired degree by adjustment 15 of the nuts 28c and 28b. By tightening up these nuts to compress the springs, the severity of the shocks imparted to the hand is increased and, by loosening the nuts, the severity of the shocks is decreased.

20 Referring now to Figure 9, there is shown another means for effecting the vibratory movement from the rotating motor. There is shown the armature shaft 9 mounted in its bearing 8 at the front end of the motor, the motor casing 1 being extended outwardly about the shaft and in the form of a cap 1b. At the outer end of the shaft 9 is secured by a pin 32a a part 32 having rearwardly extending dogs 32b which take into recesses 34b on a part 34. This member 34 is rotatably mounted upon the outer surface of the shaft bearing 8 preferably through a ball bearing 34a, the inner race of which is held in position upon the part 8 by a collar 33. The member 34 is of greater weight on one side of the axis of the shaft 9 than on the other side thereof, and therefore runs out-of-balance, rotating with the rapidly rotating shaft 9. As the member 34 is thus rotated it gives to 25 the part 8, and hence to the motor casing, a rapid vibratory movement which is in turn imparted to the hand. It will be seen that this construction relieves the shaft 9 of all strain due to parts running out-of-balance to produce the vibrations. Thus, the strain of 30 the vibrations is removed from the motor shaft, and there is no tendency to strain the shaft or increase the friction on the shaft bearings.

35 A construction such as those herein described wherein the driving motor is mounted directly upon the back of the hand, is distinctly advantageous. The motor may be very small and light and very inexpensive. The use of cumbersome flexible driving shafts is entirely done away with, and the device is many times more convenient to handle. The only connection required to the motor consists in the light flexible lead wires 17a and 17b. The motor may be very small and light and is very economical to run, being required to drive no long twisting flexible shaft as in the devices commonly in use. Preferably, as shown in Figure 5, there is provided with 40 the vibrator a rheostat 24 comprising, for ex-

ample, a pivoted arm 24b adapted to be moved over contacts 24a. By means of this rheostat the speed of rotation of the motor may be controlled. When the device is in use this rheostat may be hung on any convenient support or rested upon a table, and the only parts to in any way interfere with the manipulation of the vibrator are the light lead wires 17a and 17b.

70 As many possible embodiments may be made of the above invention and as many changes might be made in the embodiment above set forth, it is to be understood that all matter hereinbefore set forth or shown in the accompanying drawing, is to be interpreted as illustrative and not in a limiting sense.

I claim as my invention:

1. A vibrator adapted to be mounted upon the back of the hand comprising, in combination, a frame, a yielding pad secured to said frame and adapted to rest against the back of the hand, means for passing around the hand to hold said frame in position thereon, a rotary electric motor mounted upon said frame, means rotating with the armature shaft of said motor adapted to give said frame a vibratory movement, and means rotatably supporting said last-mentioned means adapted to prevent transmission of strain to the armature shaft.

85 90 95 100 105 110 115 120 125 130

2. A vibrator adapted to be mounted upon the back of the hand comprising, in combination, a frame, a yielding pad secured to said frame and adapted to rest against the back of the hand, means for passing around the hand to hold said frame in position thereon, a high speed electric motor mounted upon said frame and including a motor casing and a rotating armature shaft, a bearing member rigidly connected with the motor casing and positioned therein about the armature shaft, and means rotating upon said bearing member and driven from said armature shaft and enclosed within said casing adapted to give said casing and said frame a vibratory movement.

3. A vibrator adapted to be mounted upon the back of the hand comprising, in combination, a casing, a device therein adapted to be driven to give said casing vibratory impulses and positioned adjacent one end thereof, means for driving said device, a support upon which said casing is mounted for swinging movement about an axis adjacent the other end thereof in response to said vibratory impulses, and means for securing said support upon the back of the hand.

4. A vibrator adapted to be mounted upon the back of the hand comprising, in combination, a casing, a device therein adapted to be driven to give said casing vibratory impulses and positioned adjacent one end thereof, means for driving said device, a support upon which said casing is mounted for swinging movement about an axis adjacent the

other end thereof in response to said vibratory impulses, means for securing said support upon the back of the hand, and yielding means through which the vibrations of said casing are transmitted to said support and thence to the hand.

5. A vibrator adapted to be mounted upon the back of the hand comprising, in combination, a casing, a device therein adapted to be driven to give said casing vibratory impulses and positioned adjacent one end thereof, means for driving said device, a support upon which said casing is mounted for swinging movement about an axis adjacent the other end thereof in response to said vibratory impulses, spring means for limiting the vibratory movements of said casing, and means for securing said support upon the back of the hand.

20. 6. A vibrator adapted to be mounted upon the back of the hand comprising, in combination, a casing, a device therein adapted to be driven to give said casing vibratory impulses, a support, means for securing said support upon the hand, and means mounting said casing upon said support for relative movement with respect to said support, said last means including spring means for limiting the vibratory movements of said casing in response to said impulses.

35. 7. A vibrator adapted to be mounted upon the back of the hand comprising, in combination, a casing, a device therein adapted to be driven to give said casing vibratory impulses, a support, means for securing said support upon the hand, means mounting said casing upon said support, said last means including spring means for limiting the vibratory movements of said casing in response to said 40 impulses, and means for adjusting said spring means to change the severity of the vibrations imparted to said supporting means by said casing.

45. 8. A vibrator adapted to be mounted upon the back of the hand comprising, in combination, a casing, means for mounting said casing upon the hand, a shaft in said casing, means for rotating said shaft, an unbalanced rotary member mounted to rotate upon a part of said casing, and a driving connection between said shaft and said member.

55. 9. A vibrator adapted to be mounted upon the back of the hand comprising, in combination, a casing, means for mounting said casing upon the hand, a shaft in said casing, means for rotating said shaft, a bearing member adjacent one end of said casing in which said shaft is rotatably supported, an unbalanced rotary member mounted upon the exterior of said bearing member, and a driving connection between said shaft and said member.

60. 10. A vibrator adapted to be mounted upon the back of the hand comprising, in combination, an electric motor, a pair of frame

members, means for securing said frame members upon the back of the hand in spaced relation, a pivotal connection between one end portion of said motor and one of said frame members, a connection between the opposite end portions of said motor and the other of said frame members, and means adjacent said last end portion of said motor and driven thereby adapted to give said motor a vibratory movement about said pivot.

70. 11. A vibrator adapted to be mounted upon the back of the hand comprising, in combination, an electric motor, a pair of frame members, means for securing said frame members upon the back of the hand in spaced relation, a pivotal connection between one end portion of said motor and one of said frame members, a connection between the opposite end portions of said motor and the other of said frame members, and means adjacent said last end portion of said motor and driven thereby adapted to give said motor a vibratory movement about said pivot, said last connection including spring means through which said vibrations are transmitted to said second frame member.

75. 12. A vibrator adapted to be mounted upon the back of the hand comprising, in combination, a casing, a motor in said casing, a motor shaft for said motor, an eccentric attached to said motor shaft at the front end of the casing, a support upon which said casing is mounted for oscillations about an axis near the rear end of the casing in response to vibratory impulses induced by the eccentric when rotated, means for attaching the device to the back of the hand connected to said support, means for attaching the device to the fingers, and a plate to which said last named means is secured, the plate being located below the eccentric and the eccentric being located to the rear of the front end of the plate, the front end of the plate being farther from the axis than is the eccentric.

80. 13. A vibrator adapted to be mounted upon the back of the hand comprising, in combination, an electric motor having frame means and a rotor and rotor shaft, means for rotatably supporting said rotor shaft by said frame means, an unbalanced rotary member, means for rotating said shaft, an unbalanced member upon a part of said frame means and a driving connection between said rotary member and said rotor shaft.

85. 14. A vibrator adapted to be mounted upon the back of the hand comprising, in combination, a motor frame having an electric rotary element and a shaft therefor, means for mounting said motor frame upon the hand, a member at one end of said motor frame and carried thereby and adapted to rotatably support said shaft, an unbalanced rotary device rotatably supported by said member and a driving connection between said shaft and said rotary device.

15. A vibrator adapted to be mounted upon the back of the hand comprising, in combination, a frame, a yielding pad secured to said frame and adapted to rest against the back of the hand, means for passing around the hand to hold said frame in position thereon, an electric motor mounted upon said frame, and means rotating with the armature of said motor adapted to give said frame a vibratory movement, said motor being mounted to swing relatively to said frame about one end thereof during said vibratory movement.

16. A vibrator adapted to be mounted upon the back of the hand comprising, in combination, a frame, a yielding pad secured to said frame and adapted to rest against the back of the hand, means for passing around the hand to hold said frame in position thereon, a rotary electric motor mounted upon said frame, and means positioned adjacent one end of said motor and actuated by the rotating armature of said motor adapted to give said frame a vibratory movement, said motor being mounted to swing relatively to said frame about an axis adjacent the other end thereof during said vibration.

17. A vibrator comprising, in combination, a frame, a yielding pad secured to said frame and adapted to rest against the back of the hand, means passing around the hand to hold said frame in position thereon, an electric motor, means rotating with the armature substantially at one end of said motor adapted to give said frame a vibratory movement, means rotatably mounting said motor on said frame to provide a relative vibratory motion between said motor and said frame, and means for maintaining said end of said motor in normal position.

18. A vibrator comprising, in combination, a frame member adapted to be mounted on the back of the hand, a frame member adapted to be mounted on the backs of the fingers, said frame members being connected together by a resilient connecting means and being capable of movement independently of each other, an electric motor secured to said first-mentioned frame member, eccentric means positioned substantially above said second frame member and adapted to impart vibratory motion thereto when driven, and means forming a driving connection between said motor and said last-mentioned means.

In testimony whereof, I have signed my name to this specification this 27th day of December, 1926.

JAMES F. DORAN.

CERTIFICATE OF CORRECTION.

Patent No. 1, 896,351.

February 7, 1933.

JAMES F. DORAN, WHOSE EXECUTOR OF WILL IS JOHN C. DORAN.

It is hereby certified that error appears in the printed specification of the above numbered patent requiring correction as follows: Page 4, strike out lines 31 to 43 inclusive, comprising claim 7, and insert the following as claim 7:

"7. A vibrator adapted to be mounted upon the back of the hand comprising, in combination, a shaft, frame means rotatably supporting said shaft, means for mounting said frame means upon the hand, an unbalanced rotary member rotatably supported by said frame means and independently of said shaft, means for driving said shaft, and a driving connection between said shaft and said member adapted to transmit rotation from the former to the latter, said driving connection being constructed to prevent the reaction upon said shaft of vibratory forces caused by the rotation of said unbalanced rotary member.":

Page 4, line 116, claim 13, strike out the words "for rotating said shaft, an" and insert instead "rotatably supporting said", and line 117, same claim, insert a comma after "means"; and that the said Letters Patent should be read with these corrections therein that the same may conform to the record of the case in the Patent Office.

Signed and sealed this 16th day of May, A. D. 1933.

M. J. Moore.

Acting Commissioner of Patents.
